(57) **CLAIM**

The ornamental design for a coaxial connector, as shown and described.

DESCRIPTION

FIG. 1 is a perspective view of a coaxial connector in accordance with my new design;

FIG. 2 is a front view thereof;

FIG. 3 is a rear view thereof;

FIG. 4 is a left side view thereof;

FIG. 5 is a plan view thereof;

FIG. 6 is a bottom view; and,

FIG. 7 is a sectional view taken along a line 7—7 in FIG. 5. A right side view appears symmetric with the left side view.
